TIE DOWN FITTING

Victor Brock, 3900 39th Ave.,
Sacramento, Calif. 95824

Filed Aug. 29, 1966, Ser. No. 3,634

Term of patent 14 years

(Cl. D54—11)

FIG. 1

FIG. 2

FIG. 3

FIG. 4

FIG. 5

FIGURE 1 is a top perspective view of my ornamental design for a tie down fitting;

FIGURE 2 is a side elevational view thereof;

FIGURE 3 is a top plan view thereof;

FIGURE 4 is a bottom perspective view thereof; and

FIGURE 5 is a side elevational view in cross section taken substantially along lines 5—5 of FIGURE 3 in the direction of the arrows to show the interior configuration.

I claim:

The ornamental design for a tie down fitting, substantially as shown.
